UNITED STATES PATENT OFFICE.

FRANK H. FOLDEN, OF SIOUX CITY, IOWA, ASSIGNOR TO NORTHWESTERN MANUFACTURING COMPANY, OF SIOUX CITY, IOWA.

MULTIMOLDING CONCRETE-BLOCK MACHINE.

1,157,522.

Specification of Letters Patent. Patented Oct. 19, 1915.

Application filed December 6, 1913. Serial No. 805,061.

To all whom it may concern:

Be it known that I, FRANK H. FOLDEN, a citizen of the United States of America, residing at Sioux City, in the county of Woodbury and State of Iowa, have invented certain new and useful Improvements in Multi-molding Concrete-Block Machines, of which the following is a specification.

My invention relates to improvements in multi-molding two-end-delivery hand machines for molding concrete building blocks; and the objects of my improvement are, first, to eliminate sliding movement of the molding faces of the molds on the molded faces of the blocks when the molds are being opened and the blocks delivered from the machine; second, to dispose the actuating gearing more compactly and in a manner to facilitate its protection from the falling excess of and the scattered concrete when the molds are being filled and struck; third, to facilitate molding either two half-blocks, four quarter-blocks or one quarter-block and a three-quarter-block, in a single mold, at a single operation, without changing the lateral position or regular action of the cores as used in molding any hollow block; fourth, to provide means to better and easier control and operate the cores; fifth, to facilitate molding simultaneously, in a single mold and at a single operation, both an outer and an inner slab, suitable for walls of continuous hollow construction cross-bonded by metallic cramps or ties; and, sixth, to not only afford facilities for changing the molding faces of the molds to attain any ornamentation or diversity of surface desired on the molded blocks, but, also to change the general shape of the block; especially to mold a longitudinally-curved block, suitable for circular walls such as are employed in the construction of silos, circular storage bins, &c. I attain these objects, with others more particularly hereinafter described, by the mechanism illustrated in the accompanying drawings, in which—

Figure 1 is a vertical longitudinal section on the broken line 1, of Fig. 2, showing the molds opened, one end arranged for molding plain full-sized blocks and the opposite end arranged for simultaneously molding inside and outside slabs; Fig. 2, a top view of the open machine with parts cut away to disclose the construction; Fig. 3,

a handle-side elevation, the molds closed ready for filling; Fig. 4, a top view of Fig. 3, the cores and slab-blade standing inserted only half way into the molds; Fig. 5, an enlarged fragmental perspective view illustrating the connection of the face-plate, pallet-board, split core and dividing-plate; Fig. 6, an enlarged perspective view of the core filler; Fig. 7, a perspective view of a whole curved hollow concrete block; Fig. 8, a fragmental end view of the machine, showing the open mold as arranged for molding a whole curved block; Fig. 9, a vertical section of the closed mold as arranged for molding curved half-blocks; Fig. 10, a perspective view of the pallet-board, having the curved strike-edge-strip attached to form the outer curve or face of the block; and Fig. 11, a perspective view of one of the curved strike-edge strips to be removably seated on the top edge of the back-plates.

Similar reference numerals refer to like parts throughout all the views.

All the parts and plates composing the walls of the molds that stand directly against the concrete to form the various surfaces of the molded blocks, are moving parts of the machine movement of opening and closing molds; the block is not formed in contact with any stationary supporting part of the machine, and delivery is made by the least possible movement of the block itself, while the principal molding members are withdrawn therefrom as the molds are opened and the block removed.

The legged frame-plates 4 and 5, are spaced apart flatwise and rigidly connected by the lower cross-rods 6 and 6 and the upper stationary cross-shafts 7 and 8; these cross members have their ends tenoned to form intermediate shouldered portions of uniform lengths and their terminals are threaded to receive the nuts 9 turned home against the outer surfaces of the legged frame-plates, to form a rigid supporting frame for the whole machine. The top portions of these frame-plates are sized and squared up to receive the vertical faces of the pallet boards 10 and 11 against opposite ends of the frame-plates; the faces of the opposite mold pallets being thus spaced apart a distance equal to the thickness of two blocks and the intervening back-plates 12 and 13, in the closed molds, as shown in Fig. 4.

A pair of rocking carriers 14 and 15 are

mounted to turn on the stationary cross-shaft 7, to carry the mold members at this end of the machine. A like pair of rocking carriers 16 and 17, are reversely mounted on the stationary cross-shaft 8, to carry the oppositely-moving mold members at this opposite end of the machine. The former pair of carriers have toothed segments 18 and 18 to engage like opposite toothed segments 19 and 19 on the latter pair of carriers, connecting the mold members of opposite ends to move reversely and simultaneously. A rocking shaft 20 is boxed across below the toothed segments and carries mounted to turn therewith a pair of segmental pinions 21 and 21, disposed to engage the toothed segments 18 and 18. On an outwardly projecting end of the rocking shaft is mounted the operating handle 22. And the gearing and connected parts are speeded and timed to allow the handle a sweep of 180 degrees, to lie horizontal when the molds are fully opened or closed, convenient for manual operation and that the weight of the handle may assist to retain the molds in one of these positions, as shown in Figs. 1 and 3.

Each rocking carrier has, disposed oppositely to its toothed segment, a seat 23 to carry one end of a face-plate or mold bottom-plate 24 or 25, and has a pallet arm 26 faced at right angles to said seat: whereby, the face or bottom-plates are retained horizontal at the bottom of the molds and the pallet boards vertical thereto, when the molds are closed as shown in Figs. 3, 4, and 5: or, the face-plates swung outwardly a one-quarter turn, to the vertical position and the pallet boards swung downwardly to a horizontal face, when the molds are open as shown in Figs. 1, 2 and 8. The face-plate seats are extended into the base of the pallet arms to form the notches 27 which engage and carry the inner edges of the face-plates; while the perforated lugs 28, at the outer ends of the seats, receive the screws 29 threaded into the face-plates, to detachably fasten them to the carriers.

These face or bottom-plates are all neat lengths of the molds across the machine between the end-plates 30 and 30 or 31 and 31—or modifications of these,—as shown in Figs. 2, 4, 8 and 9. They are oppositely or double-faced, the working face being changed in the molds by changing ends with the plate. They may be any face design desired, as will be further shown, to attain a desired design of block-face; or, cross grooved to carry dividing plates when molding fractional blocks.

60 The back-plates 12 and 13, have at the ends of their lower edges the double extensions or ears 32, to straddle the rocking carriers at their angles near the swinging edges of the bottom-plates. The rod pintles 33 and 33 disposed across through these forks

or ears and the interposed carriers, hinge these parts together so that the back-plates, in effect, swing against the adjacent edges of the face or bottom-plates when the molds are closed; the back-plates of the opposite 70 end molds standing vertically against each other at the center of the machine, as shown in Figs. 3 and 4. An arched opening 34 through the frame-plates facilitates the withdrawal of the pintle rods to detach the 75 back-plates and substitute others of different designs of molding faces. At the ends of the top edges of these back-plates, outwardly-extending lugs 35 are formed to engage the notches 36 in the top edges of the 80 frame-plates to lock the back-plates in their vertical position when the molds are closed. The connecting guide-links or bars 37 and 37 have their inner ends pivoted to the outer ends of adjacent opposite back plate lugs, 85 and their outer ends pivoted at 38 and 38, the upper outer angles of the frame-plates; being thus disposed on the outer face of the frame-plate and below the top or strike edges of the mold members. The top edges 90 39 of these bars are beveled outwardly to prevent a deposit of concrete thereon. The links control the movements of the rising back-plates, so that the molded blocks and back edge of the bottom-plates turn out 95 away from the back-plates as the molds are opened; and the back-plates are correctly seated when the molds are closed.

Of the pairs of opposed end-plates 30 and 31, each plate has perforated base ears 40 to 100 align with like ears 41 on the adjacent rocking carriers to receive the removable pintles 42; whereby, the end-plates are detachably hinged to the rocking carriers to stand outwardly in the same planes as the bottom-plates, when the molds are open, as shown in Figs. 2 and 8; or to stand rightangularly upward at the ends of the bottom-plate, as shown in Figs. 4 and 9, when the molds are closed. These end-plates have a compound 105 motion at opening or closing the molds: At opening, they first swing outwardly edge-wise by the action of the rocking carriers. During this part of the movement lugs 43, projecting from the backs of the hinged bases of the end-plates, travel in the curved stopped grooves 44 in the inner contiguous faces of the frame-plates. As the end of the opening movement is approached the lugs engage the stopped ends 45 of the grooves, 110 to turn the plates flatwise and outwardly on their hinged bases: where they stand away from the ends of the molded blocks. In closing the mold, the end-plates are first 115 swung flatwise inwardly by the backs of the plates engaging the adjacent vertical edges 46 of the frame-plates—see Fig. 2—the lugs reentering and traveling down the curved grooves, as the plates swing over edge-wise to their upright posi- 120 130

tions between the ends of the back-plates and pallet-boards, as shown in Fig. 4. It is obvious that other end-plates of different design of mold-face may be substituted for any of the detachable end-plates shown.

The pallet arms each have a U-shaped loop 47, bent outwardly and backwardly from the center of its seat face, to carry and guide the core-heads 48 and 49. A laterally and outwardly bent brace 50 spans the mouth of the U to strengthen the pallet arm and clear the ends of the core heads when they are inserted or removed from the guide-loops or core-head carriers. The core-heads span the ends of the machine crosswise beneath or back of the pallet boards, each end of a head carried by a guide loop, as shown in Figs. 1 and 2.

Each core-head has a pair of legs 51 and 51, disposed right angularly, one from near each end of the head and adjacent to the carrying loop; projected outwardly, backwardly to the face of the pallet arm and pallet board. The inner or under sides of these legs have the toothed racks 52; and the upper outer faces are broadened for strength and to shield the racks and their driving pinions 53, as shown in Figs. 1, 3 and 4.

The driving shafts 54 and 54 are disposed across, one at each end of the machine, and journaled in the boxes 55 at the bases of the guide-loops. The driving pinions are mounted on these shafts to engage the racks of the legs. The projected front ends of these driving shafts are provided with the cranks 56 and 56 by the turning of which the core heads are slid forth and back in the guide-loops toward and from the pallet-boards and molds.

The core sections or halves 57 are seated on the face of the head 49 to project oppositely from the legs toward and through the pallet-board 11, as shown in Figs. 1, 2 and 4. Each core is composed of a semi-cylindrical half having a base bridge 58 to form a seat against the core head: the bridge being perforated to receive the attaching screw 59 threaded in the head. The halves of a core are spaced apart, three-eighths of an inch, the thickness of an ordinary mortar joint, to allow the insertion there-between of the dividing plates 60, in order to mold quarters, halves and three-quarter blocks. In the single core for molding a hollow half block, the double core for molding a hollow three-quarter block or the triple core for molding a hollow whole block, the space between opposite core halves is closed by the filler 61. This filler consists of an integral rectangular castiron frame having oppositely beveled lined edges 62 to fit the opposed beveled edges 63 of the core halves; these longitudinal edges of the core halves being beveled inwardly so that their peripheral

sharpened edges will contact perfectly with the dividing plates. A threaded opening 64 through the base of the filler receives a fastening screw 65 disposed through the perforation 66 disposed through the core head 70 centrally between the bridges of the opposite core halves. The halves are sharpened to form cutting edges 67 on the lower portions of their forward ends. And a portion is cut away from the lower edge near 75 the base of each half to form a discharge opening 68, to empty any concrete cut from the partially filled mold when the core is turned in.

The dividing plates 60 exceed in height 80 the depth of the closed mold, as shown in Figs. 3, 5 and 9, sufficiently to seat in the groove 69 in the face of the bottom face-plate;—in plain bottom plates this groove is filled by a special strip 70, retained by 85 screws, as shown in Fig. 8, when blocks larger than quarters are molded thereon. The up-standing edge of the dividing plate is slotted to form the loop handle 71. And has an extension 72 to overlap the top edge 90 of the back-plate and carry the dowel-pin 73 to seat in one of the dowel-holes 74 in the back-plate, to retain the top of the dividing plate against lateral displacement while filling and tamping the mold. These dividing plates and the cores are usually withdrawn before opening the mold to remove a molded block.

The pallet boards are preferably made integral of castiron. They consist of the oblong thin plate body 75, to form the molding face and are reinforced by the integral rib of rectangular plan disposed on the back of the plate, as best shown in Fig. 10. The end portions 3 of the rib are disposed flush 100 with the ends of the plate to give a convenient strong hand-hold in bearing away the blocks. The longitudinal side portions 76 are spaced inwardly from the edges of the plate to better support the center portions 105 of the plate against the strain of tamping in filling the molds. These side ribs have at their ends the backwardly-disposed hooks 77, which stand opposed to the outsides of the carrying arms 26,—see Figs. 4 and 8,—to prevent endwise displacement of the seated pallets. The backs of these hooks are inclined to facilitate seating the pallet board on the arms. And the hooks also serve as legs to elevate the board and give free circulation of air beneath and through the imposed block while it is hardening. The three central apertures 78, in the pallet-board 11, to admit the cores to and from the molds, are not modified in size or position for molding any of the hollow blocks. However, the apertures are filled or whole pallet-boards are used in molding solid blocks. And a pallet-board 10 has the single central longitudinal slot 79, to pass the par- 110 115 120 125 130 135

tion or cutting slab-blade 80, used in molding face and inside slabs for walls having a continuous hollow,—see Figs. 1, 2 and 4.

The blade 80 to cut and separate the blocks into face and back slabs, is made from a single sheet of steel plate. It has a forward cutting edge 81, and an oppositely disposed base consisting of a right angularly flanged edge 82 and the reversely-standing tabs 83 and 83, formed of partly severed portions of the plate. Through these perforated tabs fastening screws 84 are inserted to rigidly set the blade on the core head 48, and like the cores it is actuated by turning the connected crank 56. This mold is usually first filled a little more than half full, then the cutting blade is turned in and the filling for the plain inner slab is tamped in on top of it. To avoid fracturing the thin slabs, the mold is first opened, turning the slabs to stand up edgewise, then the dividing blade is withdrawn downwardly. The blade is guided in the mold by its side edges 85 sliding in the grooves 86 in the faces of the end-prints 87.

The end prints are removably attached to the mold faces of the end plates by the screws 88 disposed through their reduced ends 89,—as shown in Figs. 8 and 9. They substantially correspond in shape and position with the inserted core halves 57, and in the closed mold are disposed in alinement with the complete set of inserted cores.

When an end-quarter, a half or three-quarter block is molded, these end prints mold an end corresponding to the opposite end molded by one of the core halves. The grooves that guide the slab blade are filled by strips 90,—see Figs. 2 and 8,—removably fastened by the screws 91, when these prints are used in connection with the regular cores. The reduced ends that form an adjacent shoulder on the end-print, molds the hand-holds 92, as shown on the ends of the curved block,—Fig. 7.

Of the numerous possibilities of changes in the molding faces of the members, I have chosen to set forth those required to mold the curved blocks; which have the principal features of the regular hollow-molded straight blocks and in addition to the curvature, have, in one of the bed faces a concentrically curved groove 93, to receive a circular bonding rod laid in the bed joints of the wall. It is obvious that special integral curved bottom and back plates may be substituted to attain the changes required for molding this curved block, in like manner as are the substitute end-plates 94, shown in Figs. 8 and 9; these end plates having their faces inclined and the end-prints regularly attached to mold the splayed ends of the blocks for the radial heading joints of the wall. But, like many other changes required in the molding faces these are pref-

erably attained by adding parts to the regular faces of the working members.

A short sub-bottom plate 95, of face curvature corresponding with that required for the inner face of the wall, is imposed on the face of the bottom plate 24, to fill between the overlapping base shoulders 96 of the splayed end plates and is detachably fastened by the screws 97. A segmental strike-edge-plate 98, has its arc edge curved to agree with the outer face of the wall, and dowel-pins 99 spaced along its chord edge to agree with the dowel holes in the top edges of the back plates, and by which it is seated and retained thereon. This edge plate also has the centrally-disposed dowel hole 100 in its curved edge to receive the dowel-pin 73 of the dividing plate 60, when molding curved half-blocks,—indicated by the dotted lines 101 in Fig. 7. A like segmental strike-edge-plate 102 has the footed cleats 103 perforated to receive the attaching screws 104, by which it is detachably fastened on an edge of the pallet-board to correspond with the like edge on the back-plate. The filled mold is struck by a straight-edge spanned across on these curved edges. The curved groove-print sections 105 are spaced in a row on the face of the back plate to fill the spaces between the ends of the inserted cores. The row is disposed centrally of the space between the curved bottom plate and the curved top edge of the back plate and is curved concentrically therewith. These groove-print sections are removably attached to the mold face of the back plate by the screws 106.

Connecting shield-plates 107 and 108, are disposed across the upper and outer branches of the looped core-head guides and carriers 47, and fastened thereto by the screws 109. These bind together the opposite side members of each pair of rocking carriers into a single rocking mold carrier at each end of the machine, and shield the withdrawn cores and the slab blade, and their actuating mechanism, while the molds are being filled. The lower outer corners of these plates are notched to form the guide openings 110, to carry the sliding legs 51 with the toothed racks in engagement with the driving pinions 53.

In operation, when the molds are closed the operating gearing is beneath the mold parts which completely shield these driving connections from any falling concrete until the molds are struck and the excess of filling brushed away. As has been set forth, when the molds are opened all the molding faces, except those of the pallet-boards and bottom-plates, swing away from the molded blocks. The pallet-board, on which a block is off-borne and left to stand to cure, is first, with the imposed outwardly-turned block, drawn directly away from the bottom-plate.

Therefore, the molding faces may be modified to produce any ornamental relief or structural shape, on the exterior faces of the block, not amounting to an under-cut.

5. I claim:

1. In a concrete block mold, stationary support-plates spaced flatwise, and axially-aligned rocking mold carriers disposed adjacent to the inner faces of and pivoted to rock into and out of the space between the support-plates, in combination with mold end-plates hinged to the rocking carriers to stand backed against the support-plates and in sliding contact therewith when rocked 10 edgewise by the carriers, a tooth on the back of the hinge-base of each end-plate, a groove curved concentrically with the axis of the rocking carriers in the inner face of each support-plate to pass the tooth, and a stop 15 end to each groove disposed to engage the tooth and swing the end-plate flatwise after it is rocked edgewise out of the space between the support-plates.

2. In a concrete block mold, a pair of 25 axially-aligned and spaced rocking mold-carriers, and a mold back-plate hinged at its lower edge to the carriers, in combination with stationary support-plates having notches in their top edges, extensions at the 30 ends of the top edge of the back-plate adapted to seat in the notches, and a guide link having one end jointed to one of said extensions and the opposite end jointed to the adjacent support-plate.

3. In a concrete block mold, stationary support-plates spaced flatwise, and axially-aligned rocking mold carriers journaled adjacent to the inner faces of said support-plates to rock into and out of the space therebetween, in combination with mold end-plates hinged at one edge on the rocking carriers to stand backed against the support-plates when rocked into the space therebetween and adapted to rock edgewise into 45 and out of said space in sliding contact with the support-plates and to swing flatwise away from the molded block only when rocked out of said space.

4. In a concrete block mold, a pair of axially-aligned rocking mold carriers spaced apart, a radial pallet arm on each carrier, a removable apertured pallet adapted to seat on said arms and span the space therebetween, a core adapted to slide through the 55 aperture of the pallet, and a rearwardly disposed guide-loop on each pallet arm, in combination with a core head-bar attached to the base of the core disposed across the space between said loops and having its 60 ends seated to slide in the loops, outwardly-extended toothed guide-legs on the core head-bar, suitable gearing connected to engage the toothed legs and slide the core head-bar, and a shield-plate rigidly fastened 65 across on the guide-loops and having its

outer edge bent onto the outer ends of the loops and notched to form guideways for the toothed legs.

5. In a concrete block mold, a pair of stationary support-plates disposed in spaced relation flatwise, rocking mold carriers journaled to swing mold members in and out of the opposite ends of the space between the support-plates, and suitable mechanism to connect and rock the carriers simultaneously in opposite directions, in combination with opposite mold back-plates hinged at their lower edges to the respective carriers, end extensions on the back-plates to form seat lugs, notched seats at the top centers of the support-plates to receive together the corresponding seat lugs of opposite mold back-plates backed against each other when the molds are rocked to the inward limit, and guide-links connected to the back-plates and to said support-plates.

6. In a concrete block mold of the character herein described, vertical stationary support-plates disposed in spaced relation flatwise, and oscillatable carriers journaled to rock the mold members into and out of the space between the support-plates and having bottom-plate seats and pallet seats in angular relation, in combination with a bottom-plate having a longitudinally-curved mold face, a pallet having its top edge curved concentrically with the curvature of the face of the bottom-plate, end plates hinged to the carriers to stand backed against the adjacent support-plates with their mold faces splayed in alignment with the axis of the curved mold face of the bottom-plate when the mold members are rocked into the space between the support-plates, a back-plate hinged at its bottom edge to the carriers and having its top edge curved to agree with the top edge of the seated pallet, and a rib disposed on the mold face of the back-plate and curved concentrically with the axis of curvature of the other curved mold members.

7. In a concrete block mold of the character herein described, vertical stationary support-plates disposed in spaced relation flatwise, and rocking mold carriers journaled to rock the mold members into and out of the space between the support-plates, in combination with a back-plate hinged at its lower edge to said carriers, a longitudinally-disposed curved rib on the mold face of the back-plate and curved in a plane parallel with said mold face, and inclined-faced end-plates hinged at their bottom edges to the carriers to stand backed against said support-plates with their inclined faces in alignment with the axis of said curved rib when the mold members are rocked into the space between the support-plates.

8. In a concrete block mold of the character herein described, vertical stationary

support-plates disposed in spaced relation flatwise, and rocking mold carriers journaled to carry the molding members into and out of the space between the support-plates, in combination with end mold-plates having thinned top edges and thickened bottom or base edges hinged to the adjacent carriers to stand backed against said support-plates when rocked into the space

therebetween, whereby splayed mold end faces are formed.

In testimony whereof I have affixed my signature in presence of two witnesses.

FRANK H. FOLDEN.
